UNITED STATES PATENT OFFICE.

FRANK G. LAWSON, OF ABERDEEN, WASHINGTON.

TOOL.

1,355,053.

Specification of Letters Patent.

Patented Oct. 5, 1920.

Application filed March 1, 1919. Serial No. 280,032.

To all whom it may concern:

Be it known that I, FRANK G. LAWSON, a citizen of the United States, residing at Aberdeen, in the county of Grays Harbor and State of Washington, have invented new and useful Improvements in Tools, of which the following is a specification.

This invention relates to improved construction of peavey or cant-hook, and the object of the invention is to provide a projection or a block on one side of the sharpened part thereof for increasing the effectiveness of the peavey.

The invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:

Fig. 1 is a side elevation of a peavey constructed in accordance with my invention.

Fig. 2 is a like view taken at a quarter turn from Fig. 1.

Fig. 3 is a sectional view of a modification.

Fig. 4 is a view showing how the invention is used.

In these views, 1 indicates the stock or handle part of the peavey and 2 the socket, secured to the sharpened end of the stock. This socket is provided with the usual hook 3, which is pivoted to the socket in the ordinary manner.

In carrying out my invention, I form a projection 4 on said socket, 40 said projection being formed with or secured to the socket. Said projection is located a quarter turn from the hook.

In the modification shown in Fig. 3 the projection 4' is carried by a pointed member 45 5 and a space 6 is left between said pointed member and the projection. In this case the pointed member 5 is driven between the stock and the lower end of the socket. The lower end of the socket fitting in the space 50 6, so that the projection rests against the lower part of the socket.

The use of the invention is shown in Fig. 4 where it will be seen that when it is desired to move the beam 7 a slight distance, it is not necessary to take a new hold with the peavey as the peavey may be tilted and turned to bring the projection against the side of the beam and then by pushing upwardly on the peavey the beam will be 60 moved.

What I claim is:—

1. A peavey comprising a handle and a socket, a single hook pivoted to the socket and a laterally extending projection located 65 below the plane of the hook and spaced a quarter turn from said hook for moving the object a slight distance when the hook is not being used.

2. A peavey comprising a handle and a 70 socket, a hook pivoted to the socket and a projection removably connected with the socket, below the plane of the hook and located a quarter turn therefrom.

In testimony whereof I affix my signature. 75
FRANK G. LAWSON.
